UNITED STATES PATENT OFFICE.

WILLIAM A. EMERSON, OF PROVIDENCE, RHODE ISLAND.

DESIGN FOR A CALENDAR.

Specification forming part of Design No. **7,603**, dated August 4, 1874; application filed May 2, 1874.
[Term of Patent 3½ years.]

To all whom it may concern:

Be it known that I, WM. A. EMERSON, of Providence, in the county of Providence and State of Rhode Island, have invented certain new and useful Improvements in the Design of Calendars; and I do hereby declare that the following is a full, clear, and exact description thereof, reference being had to the accompanying drawings, and to the letters of reference marked thereon, which form a part of this specification.

The nature of my design is fully represented in the accompanying illustration, to which reference is made.

A A represent a frame surrounding the calendar, in which are formed seven vertical compartments or columns, the upper ends terminating at the intersection with a semicircle. In said semicircle, over the columns, are placed

the letters indicating the seven days of the week, and in the columns below each of said letters are placed the dates throughout the month which occur on the day above represented.

I am aware that the dates as arranged in columns are not new.

What I claim as my invention is—

The design for a calendar, consisting of the semicircular and ornamental head, and panel sides and base, as illustrated.

In testimony that I claim the foregoing as my own I affix my signature in presence of two witnesses.

WM. A. EMERSON.

Witnesses:

CHARLES SELDEN,
JOHN C. PURKIS.
